O-BENZOYLTHIAMINE DISULFIDE

Chikataro Kawasaki and Isamu Utsumi, Sakyo-ku, Kyoto, Tadashi Fujita, Otsu, and Hiroshi Kobayashi, Nishinomiya, Japan, assignors to Tanabe Seiyaku Co., Ltd., Osaka, Japan

No Drawing. Filed Aug. 30, 1961, Ser. No. 135,417

Claims priority, application Japan Oct. 5, 1960

1 Claim. (Cl. 260—256.5)

This invention relates to O-benzoylthiamine disulfide which possesses vitamin B₁-like activity, and to its preparation.

It has been known that acid addition salts of thiamine have many deficiencies such as unpleasant odor, low stability, solubility in water or limited absorption upon oral ingestion, etc.

It has also been known that some people have thiaminase, thiamine destroying enzyme in their intestines. Therefore, no effects can be seen on such people by orally administering thiamine acid-addition salts.

According to this invention, we have found that O-benzoylthiamine disulfide is free of the disadvantages of the above mentioned thiamine acid-addition salt, especially the hydrochloride. The O-benzoylthiamine disulfide of this invention occurs as colorless and odorless crystal melting at 146° to 147° C.

Its structural formula is as follows.

It has been found that O-benzoylthiamine disulfide is sparingly soluble in water. The solubilities in distilled water at various temperature are as follows.

TABLE I

Temperature (° C.)	Solubilities (Percent) by weight/volume
20	0.0060
30	0.0082
40	0.0097
50	0.0110

But the solubilities may be largely increased to more than 50% by the addition of equimolar amount of an acid (pH 3.0-3.2).

It has been known that thiamine acid-addition salts such as the hydrochloride are generally unstable in alkaline conditions.

However, it was found that O-benzoylthiamine disulfide is considerably stable even in alkaline conditions. The following Tables II and III illustrate residual rate (percent) of both thiamine hydrochloride (B₁HCl) and O-benzoylthiamine disulfide (BTDS) in alkaline conditions on accelerated ageing tests.

2

TABLE II

Residual Rate (Percent) in Aqueous Solution (2 mg./cc.) at 100° C.

pH	After 30 minutes		After 60 minutes		After 120 minutes	
	BTDS (percent)	B ₁ HCl (percent)	BTDS (percent)	B ₁ HCl (percent)	BTDS (percent)	B ₁ HCl (percent)
5.0	96.5	96.5	96.5	96.0	94.5	94.5
6.0	97.0	94.5	96.0	86.5	84.5	83.5
7.0	91.5	67.0	78.0	45.5	51.0	20.0
8.0	83.5	60.0	65.0	37.5	49.0	10.0
9.0	56.0	9.0	26.5	4.5	15.0	2.0

pH 5.0-7.0: MacElvain's buffered solution.

pH 8.0-9.0: Clark-Lubus' buffered solution.

TABLE III

Residual Rate (Percent) in Calcium Carbonate Powder (200 mg./g.)

[Relative humidity 82% at room temperature]

Substance	After 5 days	After 25 days	After 40 days
	B ₁ HCl	BTDS	
	59 100	12 94	5 94

It has been found that O-benzoylthiamine disulfide resists enzymatic degradation with thiaminase more strongly than thiamine hydrochloride on the test as described below.

The mixture of 1 ml. of substrate solution containing 20γ of B₁HCl or 22.8γ of BTDS (equivalent to 20γ of B₁HCl), 1 ml. of buffered solution and 3 ml. of the enzymatic solution prepared from cultural medium of *Bacillus thiaminolyticus* (M.M.) or *Bacillus aneurinolyticus* (K.A.) was incubated for 1 hour at 37° C., and degradation rate of the substances was assayed by thiocchrome method.

The results are as follows.

TABLE IV

45	Substance	Degradation rate (Percent)			
		Bacillus M.M., After 5 days		Bacillus K.A., After 3 days	
		×5 *	×10 *	×30 *	×60 *
50	B ₁ HCl BTDS	89.8 15.0	46.8 4.7	81.4 2.7	61.3 2.0

* Dilution of enzymatic solution.

It has been also found that the compound of this invention possesses vitamin B₁-like activity on tests on both animals and human being. Moreover, when orally administering the compound of this invention, it can be seen that blood level of total vitamin B₁ reaches the peak more rapidly, providing longer durability as compared with thiamine hydrochloride, and a larger quantity of free vitamin B₁ is excreted in urine as compared with thiamine hydrochloride. These mean better absorbability of the compound from the intestines than that of thiamine hydrochloride.

From the above facts, the O-benzoylthiamine of our invention is useful more advantageously than thiamine hydrochloride for the treatment of vitamin B₁-deficiency symptoms. It is also useful as fortifying agent suitable for use in those instances where a fortifying agent of low water-solubility is desired, for instance, in the enrichment of cereals subjected to rinsing before being cooked.

The present invention also comprises processes for preparing the O-benzoylthiamine disulfide. The O-benzoylthiamine disulfide may be prepared by reacting thiamine disulfide with an acylating agent derived from benzoic acid such as chloride, bromide or anhydride in the presence of an acid acceptor such as sodium hydroxide, sodium carbonate, potassium hydroxide, potassium carbonate or pyridine.

As the starting material, the oxidation mixture of thiamine in alkaline solution in which the thiamine disulfide is formed may also be used. Alternatively, the O-benzoylthiamine disulfide may also be prepared by treating O-benzoylthiamine with an oxidizing agent such as iodine, hydrogen peroxide or potassium ferricyanide, while maintaining the pH of the reaction mixture at alkalinity.

It has been found that the reaction proceeds most satisfactorily at a pH within the range of 10.0 to 12.0 in an aqueous medium.

The invention is further illustrated by the following examples without being limited thereto.

EXAMPLE 1

10 ml. of benzoyl chloride was dropped into a stirred suspension of 20 g. of thiamine disulfide in 20 ml. of absolute pyridine at room temperature. The mixture was stirred an additional 3 hours at room temperature and was allowed to stand overnight. The reaction mixture was concentrated under reduced pressure to remove pyridine and after adding small amounts of 20% aqueous solution of sodium hydroxide, the residue was extracted with chloroform. The extract was washed with small amounts of aqueous solution of sodium bicarbonate and water successively and was dried with sodium sulfate. Then the chloroform was removed by evaporation and 20 ml. of benzene was added to the residue whereby O-benzoylthiamine disulfide crystallized out.

Yield, 20 g., colorless prisms melting at 146°-147° C., after recrystallizing from 99% ethanol.

Analysis.—Calculated for C₃₈H₄₂O₆N₈S₂: C, 59.21; H, 5.49; N, 14.54. Found: C, 59.39; H, 5.79; N, 14.31.

Di-hydrochloride: Colorless prisms melting at 180°-181° C. (decomp.).

Analysis.—Calculated for C₃₈H₄₂O₆N₈S₂·2HCl·2H₂O: C, 51.88; H, 5.50; N, 12.74. Found: C, 52.02; H, 5.57; N, 12.74.

EXAMPLE 2

20 g. of thiamine disulfide was suspended in 200 ml. of water and 3.5 g. of concentrated hydrochloric acid was added to the suspension to dissolve the particles. The mixture was made alkaline with sodium hydroxide. 10 ml. of benzoyl chloride was dropped into the mixture with stirring on an ice bath. During the period, pH of the mixture was kept in alkalinity with 20% aqueous solution of sodium hydroxide. The mixture was stirred for an additional 3 hours at room temperature. After being adjusted to pH 7, the mixture was extracted with chloroform and the extract was treated as described in Example 1. 18 g. of O-benzoylthiamine disulfide was obtained.

EXAMPLE 3

The procedure described in Example 1 was followed

except that 20 g. of benzoic anhydride was used instead of benzoyl chloride. 16 g. of O-benzoylthiamine disulfide was obtained.

EXAMPLE 4

24 g. of sodium hydroxide in 140 ml. of water was dropped into a stirred solution comprising 70 g. of thiamine hydrochloride and 100 ml. of water on an ice bath. To the mixture was added a solution of 25 g. of iodine and 35 g. of potassium iodide in 200 ml. of water, whereby thiamine disulfide was prepared in the reaction mixture. Then 40 ml. of benzoyl chloride was dropped into the mixture at room temperature with stirring. During the period, pH was held in alkalinity with sodium hydroxide. After being allowed to stand overnight, the reaction mixture was extracted with chloroform and the extract was treated as described in Example 1. 50 g. of O-benzoylthiamine disulfide was obtained.

EXAMPLE 5

4.5 g. of O-benzoylthiamine in 460 ml. of water was neutralized with 7.5 ml. of 4 N sodium hydroxide on an ice bath. Into the solution, was dropped a solution comprising 1.3 g. of iodine, 4 g. of sodium iodide and 100 ml. of water at the same temperature with stirring. As the reaction proceeds, white precipitates appeared. The mixture was stirred for an additional 10 minutes, and the precipitates were extracted with ethyl acetate.

After the extract was washed with water and dried, ethyl acetate was evaporated at a reduced pressure and 30 ml. of benzene was added to the residue whereby O-benzoylthiamine disulfide crystallized out.

Yield 2.9 g., 75.3% of theory.

EXAMPLE 6

The procedure described in Example 5 was followed except that 0.85 g. of 30% hydrogen peroxide and 40 ml. of water were used instead of iodine-sodium iodide solution, and pH of the mixture was maintained below 12 with acetic acid during the reaction. 2.8 g. of O-benzoylthiamine disulfide was obtained. In the same way there may be used potassium ferricyanide as the oxidizing agent instead of iodine or hydrogen peroxide.

We claim:

O-benzoylthiamine disulfide of the formula
